UNITED STATES PATENT OFFICE

2,612,299

DISCHARGE APPARATUS FOR COAL
CHARGING HOPPERSChester V. McCabe, Crown Point, Ind., assignor
to United States Steel Company, a corporation
of New Jersey

Application May 5, 1950, Serial No. 160,364

3 Claims. (Cl. 222—410)

1

This invention relates to coal charging cars and more particularly to an improved discharge apparatus for the hoppers of coke oven coal charging cars.

In the operation of coke oven batteries, coal is fed from storage bins into one or more charging hoppers mounted on a charging car, said car being capable of movement along the top of the coke oven batteries in a line parallel to the battery length. Prior to my invention, the charging hoppers were either of the gravity feed or mechanical feed type, the latter including a rotary table located at the bottom of the coal charging hopper which was adapted to feed coal into a discharge or feed chute adjacent the hopper. The discharge spouts were arranged to align with charging holes or ports located in the tops of the coke ovens through which the coal was fed into the ovens.

The rotary table formed the bottom of each hopper but was detached therefrom in order to permit it to be rotated. Since the rotary table could not abut the bottom of the hopper to provide a seal therefor, it was necessary to hang a belt of flexible material from the bottom edges of the hopper to prevent spillage of coal from the opening between the sides of the hopper and the rotary table. This arrangement, however, did not prove entirely satisfactory since the bottom edge of the belt very quickly became worn by the revolving table after installation and, consequently, was ineffective as a seal. After each coal charging operation it was necessary to sweep up a considerable amount of coal and coal dust from the coke oven roof. This spillage required additional labor to maintain favorable working conditions on the coke oven tops.

If this spillage were permitted to lie on the top of the brickwork, it would act as an insulation to cause a hot spot. The hot spot would cause a spalling of the brick, resulting in a thinning of the brickwork and the development of a weak spot which would bring about premature failure of the oven roof.

The present invention is a further improvement on the apparatus disclosed in the copending application of Richard D. Wearne, Serial No. 140,403, filed January 25, 1950, for "Discharge Apparatus for Coal Charging Hopper."

It is an object of my invention to provide an improved hopper construction for coal charging cars wherein a rotary impeller having ribs on the top and bottom sides thereof is mounted internally within the hopper and sealed therein so as to render the hopper spillproof while coal is being discharged therefrom.

2

This and other objects will be more apparent after referring to the following specification and attached drawings in which:

Figure 1 is a top plan view of a coal charging car equipped with hoppers according to my invention;

Figure 2 is a sectional view through one of the hoppers looking down on the turntable of the invention;

Figure 3 is a cross sectional view taken on the line III—III of Figure 2; and

Figure 4 is a view showing a modification of the turntable of the invention.

Referring more particularly to the drawings, reference numeral 2 indicates a coal charging car having four coal hoppers 4 mounted thereon. A downwardly directed discharge spout 6 is mounted on the car laterally adjacent the bottom of each of the hoppers 4 with its entry end 8 communicating with the interior of the hopper. The bottom of each hopper is formed by a circular plate 10 which may be attached to the bottom edge of the hopper wall by suitable means such as a continuous weld 9. The discharge spout 6 is bolted or otherwise fastened to the bottom of plate 10 as at 12 to prevent coal spillage at that point.

An opening 14 is provided through the center of plate 10. An upper coupling half 16, having a rounded hub portion 18 projecting from its body portion 26 and a square shaped stub shaft extension 20 projecting from the rounded hub 18, is mounted on the bottom of hopper 4 with its hub 18 fitted into the opening 14. Stub shaft 20 extends above the bottom plate 10 to support a turntable 22 having a square hole 24 through the center thereof adapted to receive the stub 20. The hole 24 is so sized and shaped that stub 20 fits snugly therein.

The annular body portion 26 of coupling half 16 is provided with a series of bolt holes 28 adjacent its periphery which accommodate bolts 30 whereby the upper coupling half 16 is connected with a bottom coupling half 32. The bottom coupling half 32 is keyed on a vertical shaft 34 of a gear unit 36. The shaft 34 is rotated by means of a motor 38 and reducing gear 39 through a worm 40 and worm wheel 42 and supported by thrust bearings 44. The thrust bearings 44 are of the roller type and are sufficiently rugged in construction so as to enable the gear unit 36 to carry all of the weight of the top and bottom coupling halves 16 and 32, the turntable 22, and the load of coal carried by the turntable. This arrangement eliminates any pressure on the bottom of the hopper and any excess friction result-

ing therefrom which would necessitate increased power for rotating the turntable. As seen in Figure 3, the turntable 22 is provided with a sealing ring 46 welded to its underside surrounding the hole 24. Thus, the turntable 22, being supported by the stub shaft 20 and riding clear of the bottom plate 10, is carrying the entire load of the coal in the hopper. This load, transmitted through the upper and lower coupling halves 16 and 32, is supported entirely by the gear unit 36.

The sealing ring 46 overlies the space between the stub shaft 20 and the opening 14 to prevent leakage of coal through the opening 14 along the side of the rounded hub 18 of coupling half 16. In order to insure the rotation of turntable 22 in a horizontal plane, and to provide means of adjustment for leveling the turntable in the event bottom plate 10 becomes warped, shims 48 are inserted between the sealing ring 46 and the bottom plate 10, as seen in Figure 3.

The turntable 22 is provided with ribs 50 projecting from the top surface thereof to impel the coal into the entry end 8 of spout 6. Ribs 50 extend radially from the edge of hole 24 to the edge of the plate so as to impel the coal into the entry end 8 of the discharge spout 6 when the turntable is rotated in the direction indicated by the arrow in Figure 2. Ribs 52, corresponding to the ribs 50, are provided on the underside of turntable 22 so as to sweep out the coal that accumulates in the clearance space between the turntable and the plate 10. I have found that if means were not provided to sweep out this coal, it would pack under the rotating turntable and in a short time would interfere with its free rotation and thus create an overload which would cause the driving motor to stall. Ribs 52 extend radially from the outer periphery of the sealing ring 46 to the outer edge of turntable 22.

In Figure 4 I have shown a modification of the turntable 22 in which the upper ribs 50 and the lower ribs 52 are positioned at an angle to the radial. This arrangement may be preferred to insure the coal being swept into the discharge spout 6 by the sweeping action of the ribs.

An annular seal 54 having an inside grooved portion 56 is welded to the bottom side of plate 10 with grooved portion 56 concentric with the opening 14. A packing 58 of hemp or other suitable material is packed into the groove 56. Seal 54 prevents fine coal and coal dust from leaking between hole 14 and the hub 18 of coupling half 16. The diameter of the hub is only slightly less than the diameter of opening 14 so that it fits snugly but is freely rotatable therein. The body portion of seal 54 is provided with a ring of drilled and tapped holes 60. A split annular keeper plate 62 is attached to the bottom side of seal 54 by means of cap screws 64 to hold the packing 58 in place. The cap screws 64 fit into the drilled and tapped holes 60. Keeper plate 62 is made in two arcuate sections so that it may be easily removed to replace packing 58 when necessary.

As seen in Figure 1, all four hopper feeds are driven in unison by a single motor. The reason for this arrangement is that the four hoppers carry an exact charge for one coke oven which is provided with four charging holes. Thus, by driving the four hopper feeds in unison, the oven is charged quickly and evenly. It will be noted that the number of hoppers on the charging car may be varied in accordance with the design and size of the coke ovens in the battery. Each gear unit may be connected to an individual motor if desired.

In operation, coal is loaded into each of the hoppers in the conventional manner through an opening in its top. The charging car is then propelled along the coke oven battery roof until the discharge spouts are positioned directly over the charging holes of the coke oven to be charged. The coke oven is then charged by starting the motor 38 which rotates the turntables 22 through gear units 36 to impel the coal from the hoppers to the discharge spouts. Since the bottom of each hopper is completely sealed, there is no spillage or leakage of coal during the entire charging operation.

While one embodiment of my invention has been shown and described, it will be apparent that other adaptations and modifications may be made without departing from the scope of the following claims.

I claim:

1. In a charging hopper for coke ovens or the like having side walls and a bottom plate sealed thereto, and a discharge spout at one side communicating with the interior of the hopper, the combination therewith of a turntable spaced slightly above said plate, said turntable comprising a horizontal circular plate having a center opening therethrough, a plurality of spaced projecting ribs on both the upper and lower face of said turntable, said bottom plate having an opening therethrough communicating with the center opening in said turntable, a coupling including a separate upper and lower section removably joined together, said coupling being disposed subjacent said bottom plate with the upper section thereof projecting upwardly through the opening in the bottom plate to fit snugly in the center opening of said turntable, driving means connected to the lower section of said coupling for rotating the same, roller type thrust bearings for supporting the coupling, the turntable and the load thereon, a sealing ring disposed between said turntable and said bottom plate overlying the space between the projecting portion of said upper section and the edge of the opening in said bottom plate, and a seal extending around the upper section of said coupling and mounted on the underside of said bottom plate overlying the space between said upper section and the edge of said opening in the bottom plate.

2. In a charging hopper for coke ovens, the combination therewith according to claim 1 in which the said sealing ring is secured to and forms part of the turntable.

3. In a charging hopper for coke ovens, the combination therewith according to claim 1 characterized by said driving means including a vertical shaft keyed to said lower section, a worm wheel disposed circumferentially around said shaft, a worm in engagement with said worm wheel, and motor means for rotating said worm.

CHESTER V. McCABE.
